Primary Examiner — Adir Aronovich*Assistant Examiner* — Ethiene Salgado-Rodriguez(74) *Attorney, Agent, or Firm* — Dickstein Shapiro LLP(57) **CLAIM**

I claim the ornamental design for a case, as shown and described.

DESCRIPTION

FIG. 1 is a front and right side perspective view of a case showing my new design;

FIG. 2 is a rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in FIGS. 1-8 are for purposes of illustrating features of the case which form no part of the claimed design.
